United States Patent Office

Des. 197,906
Patented Apr. 7, 1964

197,906

NECKLACE SHORTENER

Ernst Bohlinger, 31-15 25th Ave., Astoria, Long
Island 5, N.Y., and Samuel Friedman, 556 Ave. Z,
Brooklyn, N.Y.

Filed Oct. 21, 1963, Ser. No. 77,057

Term of patent 3½ years

(Cl. D45—4)

FIG. 1.

FIG. 2.

FIG. 3.

FIG. 4.

FIG. 1 is an end elevational view of a necklace shortener, showing our new design,

FIG. 2 is a top plan view thereof,

FIG. 3 is a bottom plan view thereof,

FIG. 4 is a sectional view taken on line 4—4 of FIG. 2, and

FIG. 5 is a sectional view taken on the same line but with the parts opened.

We claim:

The ornamental design for a necklace shortener, substantially as shown.
